[57] CLAIM

The ornamental design for a cover for protecting fingers while cutting hair, as shown and described.

DESCRIPTION

FIG. 1 is an exploded perspective view of a cover for protecting fingers while cutting hair showing our new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom plan view thereof.

The crosshatch surface shading shown in all views is understood to repeat throughout the indicated area.
